J. H. LANE AND C. D. HOUSE, OF LAKE VILLAGE, NEW HAMPSHIRE.

Letters Patent No. 97,526, dated December 7, 1869.

IMPROVEMENT IN KNITTING-MACHINE NEEDLE.

The Schedule referred to in these Letters Patent and making part of the same.

To all whom it may concern:

Be it known that we, J. H. LANE and C. D. HOUSE, of Lake Village, in the State of New Hampshire, have invented a new and useful Improvement in Knitting-Machine Needles; and we do hereby declare that the following is a full, clear, and exact description of the same, reference being had to the accompanying drawings and letters of reference marked thereon, making a part of this specification, in which the drawing is a plan view of a latch with my improved rivet.

This invention consists in passing a small pin, of malleable metal, through the flat part of a latch for knitting-machine needles, and then widening the ends of such pin, so as to prevent them from being drawn in either direction through the latch.

To enable those skilled in the art to make and use our invention, we now proceed to describe its construction and operation.

Similar letters in the drawings refer to like parts.

A is an ordinary knitting-machine-needle latch, through the lower flat end of which is passed a small pin, *a*, of malleable metal, the ends of which are then widened out so that they cannot be drawn out through the hole in which the pin is placed.

The latch, with its pin thus prepared, is then placed in position in the needle B, by spreading open the slot

in the latter until the pin *a* may be placed lengthwise across the slot, and its ends inserted in the slots previously prepared in the sides of the needle for the purpose, which are then to be pressed toward each other into their original position, thus fastening the latch.

It is evident, from the foregoing, that the pin *a* cannot work out of the latch in either direction, as a mere pivot is liable to do, and furthermore, that in case of a breakage of the pin, its place may be supplied by a new one, whereas, if a trunnion, rigidly attached to the latch, breaks, the latch itself has to be thrown away.

What we claim as new, and desire to secure by Letters Patent, is—

The knitting-machine needle herein described, having elongated openings in the sides, to receive the flattened ends of the pivot on which the latch turns, said pivot being flattened after it is passed through the latch, and the latch and its pivot being secured in place in the shank of the needle, by springing the slot in the shank open.

J. H. LANE.
C. D. HOUSE.
